UNITED STATES PATENT OFFICE.

JOHN WILLIAM HUNTER, OF WHEELING, WEST VIRGINIA.

DESIGN FOR A GLASS VESSEL.

SPECIFICATION forming part of Design No. 26,062, dated September 22, 1896.

Application filed May 8, 1896. Serial No. 590,781. Term of patent 3¹ years.

To all whom it may concern:

Be it known that I, JOHN WILLIAM HUNTER, of Wheeling, in the county of Ohio and State of West Virginia, have invented a new and original Design for Glass Vessels, of which the following is a full, clear, and exact description, reference being had to the accompanying drawings, forming part of this specification, in which—

10 Figure 1 is a perspective view, and Fig. 2 is a vertical sectional view, of a vessel embodying my design.

15 My design consists of a glass vessel having a lid or cover of the shape herein described and shown.

In the drawings, 2 represents a vessel having its top covered by a lid having a dish-shape side portion 3 and a central circular projection 4.

I claim—

The design for glass vessels substantially as herein shown and described.

In testimony whereof I have hereunto set my hand.

JOHN WILLIAM HUNTER.
